UNITED STATES PATENT OFFICE

GEORGE E. JUDD, OF BOSTON, MASSACHUSETTS

TICKET AND TICKET CABINET

Application filed August 22, 1929. Serial No. 387,718.

In a co-pending application Serial No. 387,719, filed August 22, 1929 I have shown and described a novel apparatus for holding tickets such, for example, as those used in subscribing to or making reservations for a course of concerts or a series of entertainments or public events of any kind. The apparatus is designed especially for use in connection with the sale of tickets to the theatre, opera, concerts, lectures, or the like, and it comprises a case or cabinet having a multiplicity of pockets each adapted to hold a ticket with the end of the ticket projecting from the pocket at the front of the case. The pockets correspond in number and arrangement to the number and arrangement of the seats to be sold, and the case or cabinet is placed in such a location that the public has access to it. In using the apparatus a person goes to the case, selects the seat or seats which he wishes to occupy, removes the ticket or tickets from these locations, signs his name and address on the tickets, and deposits them in the box office, or transmits them to the management in any convenient manner.

The present invention relates to apparatus of this general character. It aims to make such apparatus more completely automatic and to minimize any tendency to take tickets out of the case without making a subscription.

The nature of the invention will be readily understood from the following description when read in connection with the accompanying drawings, and the novel features will be particularly pointed out in the appended claims.

In the drawings,

Figure 1 is a perspective view, somewhat diagrammatical, of part of a case or cabinet constructed in accordance with this invention;

Fig. 2 is a vertical sectional view on a large scale showing certain details of construction of the case, an intermediate portion of the structure being omitted;

Fig. 3 is a perspective view of one of the front plates or strips of the case;

Fig. 4 is a perspective view, partly in sec-

tion, illustrating additional structural features of the case; and

Fig. 5 is a plan view of the ticket or subscription slip (hereinafter referred to as a ticket) which may conveniently be used in the case.

The case or cabinet partly illustrated in Fig. 1 is shown more completely in my pending application above referred to. It includes panels 1 and 2 which in a typical instance are, say, five or six feet high and are supported in upright positions on castors 4. Each panel holds the tickets for a given section of the hall, theatre, or opera house, and it is provided with a multiplicity of pockets which are laid out or arranged in accordance with the floor plan of the particular section to which it relates. For example, in Fig. 1 the pockets in the panel 1 are arranged in accordance with the seating arrangement of the floor or orchestra of a particular hall. The panel 2 is laid out according to the floor plan of the first balcony. This arrangement, of course, will vary with the individual hall, theatre, or the like, for which the apparatus is used. One pocket or slot for a ticket is provided for each seat, and the pockets correspond in number and arrangement to the number and arrangement of the seats.

The tickets used in the case may conveniently be of the form shown in Fig. 5. Referring to this figure it will be seen that this ticket comprises a relatively long narrow portion 5, hereinafter designated as the "shank," and a widened end 6 with abrupt shoulders 7-7 at the junction of said portions 5 and 6. A slot 8 extends longitudinally through the greater part of the shank 5 but stops short of the ends of the ticket so that both ends of the slot are closed. A tear line 9 is made transversely across the shank and partly divides it into upper and lower sections *a* and *b*, respectively. The lower section *b* contains the subscription and therefore bears appropriate printed matter, as shown in Fig. 5, including a blank for the name and address of the subscriber. Preferably both the widened end 6 and also the section *b* bear figures, letters, or words identifying the seat which

80

90

95

100

this particular ticket designates. The part *a* of the ticket may also bear appropriate memoranda concerning the series of entertainments for which the subscription is to be made.

It is intended that the subscriber shall write his name and address on the ticket section *b*, tear off the section *a* at the tear line 9 and take the latter section away with him, leaving the section *b* in the case.

In the particular construction shown each panel of the cabinet includes a rear wall 10 and a front wall spaced therefrom and comprising a plurality of metal strips 12. These strips are nailed to a series of upright spacing bars 13 which are, in turn, secured to the rear wall 10 so that a series of vertical channels are provided between the front and rear walls, these channels being separated from each other by the spacing bars 13. The strips 12 are spaced vertically from each other and the points where the spaces between them cross the channels just mentioned form the pockets or ticket receiving slots, such as those indicated at 14, Fig. 4. These slots also are shown in section in Fig. 2. In this particular construction narrow metal strips 16 are located vertically between the spacing bars 13 and the horizontal strips 12 of the front wall, these strips 16 serving to narrow the slots 14 while leaving the channels in the case somewhat wider.

Extending rearwardly from each of the strips 12 immediately below the respective slots 14 are projections which may consist of lugs or prongs 15, Fig. 3, struck up from the metal of the strip 12, or they may consist of pins 15', Fig. 4, set into or welded to the backs of the strips 12. In fact, these projections may be formed in a variety of ways. Each projection extends into the slot 8, Fig. 5, of the ticket located in the pocket or slot in the panel immediately above the respective projection and serves to prevent the withdrawal of the ticket upwardly out of the pocket or slot. This will be clear from an inspection of Fig. 2. At the same time this arrangement permits the partial withdrawal of each ticket from its respective pocket by a movement upwardly through the slot 14 so that the subscriber can sign his name and address, tear off the ticket at the tear line 9 and release it, thus allowing the signed section *b*, Fig. 5, of the ticket to drop 55 back into one of the vertical channels where it will fall by gravity into a drawer or box 17, Fig. 2, in the lower part of the panel. This drawer or box is locked and can be opened only by the manager or someone 60 authorized by him to do so. The purchaser may go to the box office and pay his subscription or he may send a check later to the manager.

In Fig. 2 the tickets have been shown relatively thick so that the shanks appear more

crowded in the channels than is the case in actual practice.

It will be noted that when a ticket is in one of the pockets in the case the shoulders 7—7 rest on the lower edge of one of the slots 4 and that further downward movement of the ticket in the pocket is prevented by the shoulders. When a ticket of this construction is used, the projections 15 or 15' perform simply the function of dogs to enter the slots in the tickets and prevent their complete removal from the pockets. It is contemplated, however, that the projections or dogs 15—15' may also serve the additional function of holding the tickets in their normal positions in the case, thus making it unnecessary to use a ticket having a widened end 6. Such a ticket is shown at 18, Fig. 4. It is held in position with its upper end projecting from the case by the engagement of one of the dogs 15 or 15' with the upper end of the slot 8' in the ticket.

The arrangement of ticket case and tickets above described has substantially the same advantages as that in the construction shown in my earlier application, above referred to. In addition it minimizes the tendency for irresponsible removal of the tickets from the case.

While I have herein shown and described a convenient embodiment of my invention, it will be understood that the invention may be embodied in other forms without departing from the spirit or scope thereof.

Having thus described my invention what I desire to claim as new is:

1. The combination of a ticket case having a multiplicity of pockets therein corresponding in number and arrangement to the number and arrangement of the seats to be sold, each pocket being adapted to receive the shank of a ticket leaving the end of the ticket exposed at the front of the case, and tickets in said pockets, said pockets and tickets having parts cooperating to permit only a partial withdrawal of each ticket from its respective pocket merely by a longitudinal pull on the ticket.

2. The combination of a ticket case having a multiplicity of downwardly extending pockets therein each adapted to receive a ticket, tickets in said pockets, each of said tickets being slotted, and parts in said pockets cooperating with said slots to prevent the complete withdrawal of each individual ticket from its respective pocket merely by a longitudinal pull on the ticket but permitting such a pull to effect a partial withdrawal of the ticket therefrom.

3. A ticket case having a multiplicity of downwardly extending pockets therein corresponding in number and arrangement to the number and arrangement of the seats to be sold, each pocket being adapted to receive the shank of a ticket leaving the upper end

of the ticket exposed at the front of the case, tickets in said pockets, each ticket having a slotted shank portion and an enlarged head, means cooperating with the slots in the tickets for preventing the complete removal of each ticket from its pocket merely by an upward pull thereon but permitting its partial withdrawal upwardly therefrom by such a pull, and channels in said case through which severed shank portions of the tickets may 10 drop by gravity from said pockets.

4. A ticket case having a multiplicity of pockets therein corresponding in number and arrangement to the number and arrangement 15 of the seats of an auditorium, each pocket being adapted to receive a ticket, means for preventing the complete removal of the tickets from the pockets merely by a longitudinal pull on the tickets but permitting 20 their partial withdrawal, and tickets in said pockets, each ticket having a tear line dividing it into two parts, and with a seat designation on one of said parts and a subscription blank on the other.

25 5. A ticket case having a plurality of pockets therein corresponding in number and arrangement to the number and arrangement of the seats of an auditorium, tickets in said pockets, each ticket bearing a seat designating 30 portion and a contract portion, and means in said pockets cooperating with the tickets to allow partial withdrawal of the tickets from their pockets to make the contract portion thereof accessible, but preventing 35 their complete removal from the pockets.
